UNITED STATES PATENT OFFICE.

CASPER SCHAEFER, OF SAG HARBOR, NEW YORK, ASSIGNOR TO THE FAHY'S WATCH-CASE COMPANY, OF SAME PLACE.

DESIGN FOR A KNUURLING-TOOL.

SPECIFICATION forming part of Design No. 20,317, dated November 18, 1890.

Application filed March 23, 1888. Serial No. 268,286. Term of patent 14 years.

To all whom it may concern:

Be it known that I, CASPER SCHAEFER, a citizen of the United States, residing at Sag Harbor, in the county of Suffolk and State of New York, have invented and produced a new and ornamental Design for a Pattern for a Knurling-Tool, of which the following is a full, clear, and exact description, reference being had to the accompanying drawing, forming part thereof, which represents an edge view of the head of a knurling-tool having my pattern on the periphery of the same.

The leading features of my design consist of a main feathery whirl having a small feathery whirl within its outer end located on the periphery of the head and a straight line running around the design and serving to mark off the pattern distinctly.

1 is the periphery of the head of the knurling-tool, having beveled portions 2 and 2^a and straight lines 2^b.

3 is a main feathery whirl arranged lengthwise of the periphery.

4 is a small feathery whirl within the outer end 5 of the main whirl.

A small feathery whirl 6 is shown between the main whirls, having a tendril 7. It will be seen that the alternate pattern-whirls are reversed.

Having thus described my invention, the following is what I claim as new therein and desire to secure by Design Letters Patent:

The design for a pattern for the periphery of the head of a knurling-tool, substantially as herein described and shown.

CASPER SCHAEFER.
